RANGE STRUCTURE

Leo E. Mendel and Frederick J. Port, Chicago, and
Charles L. Turner, Oak Park, Ill., assignors to
Cribben and Sexton Company, Chicago, Ill., a
corporation of Illinois

Application April 12, 1946, Serial No. 661,748

4 Claims. (Cl. 126—39)

1

This invention relates to range structure. The invention is particularly useful in connection with a range having a grate mounted over a burner and in which it is desired to move the grate relative to the range top.

An object of the invention is to provide a range structure in which a grate is mounted in the upper portion of the range and over a burner, means being provided for adjusting the grate relative to the range top whereby a vent for the flow of combustion gases is provided for the burner below the grate. Yet another object is to provide a range structure in which a grate is mounted above a burner and in which means accessible from the front portion of the range is provided for controlling the elevating or lowering of the grate with respect to the range top. Yet another object is to provide a range structure in which means are provided for the raising of a grate above a burner, together with means for latching or locking the grate in a fixed position until it is desired to restore the parts to their original position. A further object is to provide a range structure in which a grate is mounted above a burner in such an arrangement as to provide a flush surface with the top of the range, and to approach the appearance of a range top with no opening, and means being provided for adjusting the position of the grate relative to the top when it is desired to use the burner, means also being provided for automatically controlling the flow of gas to the burner when the parts are adjusted for such operation of the burner. Yet another object is to provide a range top with a plurality of burners and grates thereover, together with means for raising or lowering the grates by electrical means. Yet another object is to provide a locking device for automatically closing gas valves, singly or jointly, whenever the position of the grates is such as to prevent egress of combustion products. A still further object is to provide in a range structure a lock-stop device for fixing the height of the grates relative to the stove top so as to permit proper combustion. A further object is to provide control knobs or other objects for operating the electrical power system for raising or lowering the grates. Other specific objects and advantages will appear as the specification proceeds.

The invention is illustrated, in a preferred embodiment, by the accompanying drawings, in which—

Figure 1 is a broken vertical sectional view of a range embodying our invention; Fig. 2, a sectional detail view, the section being taken as

2

indicated at line 2—2 of Fig. 1; Fig. 3, a sectional detail view, the section being taken as indicated at line 3—3 of Fig. 1; Fig. 4, a perspective view of a locking bar employed; and, Fig. 5, a broken vertical sectional view of a portion of the range showing a modified structure for the elevation of the disk grate.

In the structure illustrated in Figs. 1—4 inclusive, 30 designates the upper part of a range 10 which for purposes of illustration is shown as a gas range. The range top 31 may contain one or more burner openings, one of which is shown in Fig. 1 and designated 32. A disk grate 37 is carried within burner opening 32 by a shaft 38 having the lower portion 39 thereof received within a lifting solenoid 40. The lower end of shaft 38 is reduced in diameter so as to provide a locking shoulder 41.

It will of course be understood that the disk 20 grate shown is illustrative, and other types of grates may be employed as desired.

Grate 37, it will be noted, is formed to fully close the burner opening 32 when grate 37 is in the retracted position shown in solid lines in Fig. 1. When the burner is in use, grate 37 is raised to the position shown in dotted lines in Fig. 1, thus providing ample space between it and range top 31 to permit the escape of the products of combustion.

In order to latch the member 38 in its upper position, we provide a bar 42 having a bifurcated forward end 43, a rear portion 44 encircled by a spring 45, and a further portion 46 received within a solenoid 47. The member 42 is guided within a housing 48 so that when the member 42 is thrust outwardly under the influence of spring 45, the forward end portion 43 will extend under the shoulder 41 to lock the upright 38 in the elevated position shown in dotted lines.

To control the flow of gas from the manifold 49, we provide a valve member 50 having a valve plunger 51, and the plunger 51 is engaged by one end of a shaft 52 pivoted upon bracket 53. The inner end of shaft 52 is pivotally secured to the upright 38 at 54. Thus, upon the raising of the upright 38, the outer end of shaft 52 will drop, allowing the valve plunger 51 to drop, thereby opening the flow of gas into the channel valve 55 leading to the burner 56.

Any suitable means for controlling the foregoing electrical mechanism may be employed. In the illustration given, we provide a knob 57 equipped with a sleeve 58 keyed to a shaft 59 leading to the valve 55. The sleeve 58 is provided with a brush contact member 60 adapted

to be brought into engagement with the spring contact 61 and also with the spring contact 62.

The knob handle 57 may be provided with any suitable means for locking the handle in an interior position, and also with means for stopping the movement of the handle at the desired point. Secured to the knob 57 is an annular member 63 having peripheral notches 64 receiving inwardly-turned splines 65 carried by the fixed casing ring 66. At its inner side, the ring is provided with an annular recess 67 through which the member 63 may freely rotate. The contacts 61 and 62 heretofore described may be carried by an arm 68 secured, by the means illustrated, to the front wall portion of the ring.

In the operation of the structure illustrated, the knob member 57 may be pushed inwardly so as to bring the contact 60 first into engagement with the spring contact 61 and then into engagement with the spring contact 62. The spring contact 61 is connected by electrical cable to the solenoid 47. The closing of the circuit by contact between member 60 and the spring contact 62 results in energizing the lifting solenoid 49; this produces a lifting of the upright 38 and disk 37, as illustrated. After the upright 38 is raised, the first breaking of contact occurs between the members 60 and 61 (because the contact member 60 is advanced beyond the contact 61), thus de-energizing solenoid 47 and permitting the spring 45 to urge the locking member 42 inwardly to bring the head portion 43 into engagement with the shoulder 41 of upright 38. Thus, the grate 37 is locked in the elevated position illustrated in dotted lines. At the same time, the upward movement of the upright 38 lowers the outer end of lever 52 and permits the plunger 51 of valve 50 to drop, thus permitting flow of gas from the manifold therethrough to the valve 55. As the knob 57 is rotated to control the flow of gas through valve 55, the contact between the member 60 and spring contact 62 is broken so that the lifting solenoid 49 is deenergized. However, since the upright 38 is already latched in its raised position, there is no tendency for the grate 37 to fall.

To lower the grate 37 and to restore the parts to their initial position, the converse of the operations described is followed. As the knob 57 is rotated, electrical circuit is made through the lifting solenoid 49 which relieves the strain upon the latching member 42. As the spring within knob 57 forces it back to its original position, the solenoid 47 (by the momentary contacting of member 60 with the contact 61) is energized to retract the latching member 42. Further retraction of the knob 57 de-energizes the solenoid 49, and the upright 38 and disk 37 move downwardly to their original position. Complete restoration of knob 57 to its original position then de-energizes solenoid 47 by breaking contact between members 60 and 61. The dropping of the upright 38 also results in the closing of the plunger 51 and thereby the valve 50.

In the modification shown in Fig. 5, the structure is identical with that already described in Fig. 1, except that a manual element is substituted for the solenoid latching element. In this structure, the knob 69 is provided with a push-pull wire 70 received within cable 71, and the wire engages a spring-urged latch member 72. The latch member 72 is adapted to engage below a shoulder 73 of the upright 74 when the upright 74 is elevated by the solenoid 75. In operation, when the knob 69 is pushed inwardly,

the wire 70 presses the catch 72 into latching position below the shoulder 73, aided by the spring 76. When the handle 69 is to be moved outwardly to bring about the lowering of the upright 74, the spring contact arm 77 is in contact with the member 78 and this closes the circuit leading through cable 79 to the solenoid 75 so as to place lifting force upon the upright 74. At the same time, outward pull upon the wire 70 disengages the latch 72 from the shoulder 73, and upon the breaking of the contact between members 77 and 78 and the de-energizing of solenoid 75, the upright 74 and disk or grate 37 fall to their initial position.

15 While the invention is particularly adapted for use with gas ranges, it will be understood that the invention is also applicable to other fuel-burning structures and other heating devices. Further, while we have shown electrical means for effecting the movement of the grate and top relative to each other and also the control mechanism employed therewith, it will be understood that other power devices may be employed to produce the movements herein described.

20 Furthermore, if desired, the structure employed may be used for raising all of the grates together or raising the grates in groups, rather than singly.

25 While in the foregoing description we have set forth certain embodiments of the invention in considerable detail, it will be understood that such details may be varied widely by those skilled in the art without departing from the spirit of our invention.

30 We claim:

1. In a range, a frame providing a range top member having at least one burner opening, a burner aligned with said opening, a movably mounted grate member over said burner, and 35 solenoid-operated means for moving the grate between lowered and raised positions, and latch means operative releasably to secure the grate in its elevated position.

2. In a range, a frame providing a range top having at least one burner opening, a burner aligned with said opening, a grate movably mounted over said burner, a shaft extending through said burner and engaging said grate, a solenoid associated with the lower end of said shaft, means for energizing said solenoid to effect vertical movement of said grate, latch means operative releasably to secure the grate in its elevated position, and means controllable from the front of the range for releasing the latch means for lowering the grate.

3. In a range, a frame providing a range top having a burner opening, a burner aligned with said opening, a grate over said burner, solenoid means for raising said grate member, solenoid-actuated latch means for releasably securing said grate member in elevated position and releasing the same to lower it, and a handle equipped with contact means for energizing and de-energizing said solenoids to effect vertical movement of said grate and the unlatching thereof when in elevated position.

4. In a range, a frame providing a range top having a burner opening, a burner aligned with said opening, a grate over said burner, solenoid means for raising said grate member, solenoid-actuated latch means for releasably securing said grate member in elevated position and releasing the same to lower it, and a handle equipped with contact means for energizing and de-energizing said solenoids to effect vertical

movement of said grate and the unlatching thereof when in elevated position, said handle being equipped with stop means limiting the movement thereof and with means for locking said handle in a predetermined position.
